UNITED STATES PATENT OFFICE

2,457,223

PIVOTED OUTER JAW PIPE WRENCH

Clyde H. Green, Macedonia, Ohio

Application November 6, 1945, Serial No. 627,001

1 Claim. (Cl. 81—98)

1

The present invention relates to a pivoted outer jaw pipe wrench and the primary object thereof is to eliminate the pivot pin commonly employed in pipe wrenches with a fixed jaw and a pivoted jaw.

Another object of the invention is to provide a pipe wrench of simpler and more compact construction than that of prior devices.

With the foregoing and other objects and advantages in view, the invention consists of the novel construction and arrangement of parts hereinafter described and claimed.

In the accompanying drawings illustrating the invention:

Figure 1 is a side elevation of the invention.
Figure 2 is a rear elevation thereof.

Figure 3 is a detail perspective view of the pivotal jaw.

Figure 4 is a detail, fragmentary perspective view of the fixed jaw.

Like numerals in the description and drawing designate the same parts of construction. 1 is the fixed jaw member of the wrench having an elongated wrench handle 2 and 3 is the pivotal jaw member. Both jaws are provided with serrations or teeth 4 arranged in conventional manner transversely.

The jaw of member 1 is formed in the rear of the teeth with a transverse curvilinear groove 5 with the upper rear thereof terminating in a shoulder 6. Shoulder 6 projects above the plane of the teeth 4. The bottom of the groove is slightly arched or bowed upwardly from its ends to the middle thereof as at 7. A threaded bolt hole 9 passes horizontally through the back of the jaw and is positioned to intersect the bottom of groove 5 at approximately the middle.

The pivotal jaw member 3 is formed on the rear with a downwardly and rearwardly projecting, transverse lug 10 of cylindrical form. This lug 10 is provided on its underside with an arcuate slot 11 which is coaxial with the round portion of lug 10. The lug is adapted to slide endwise into groove 5 in which position the arcuate slot 11 is contiguous to the bottom thereof and in alignment with the horizontal bolt hole 9. When so positioned a bolt 12, threaded on its end, is passed through the fixed jaw member 1

2

and threaded into the end of bolt hole 9. The round shank of the bolt projects into the groove 5 and arcuate slot 11, thus permitting pivotal movement of jaw member 3 but preventing axial movement of lug 10 in the groove. Moreover, the enlarged outer ends of the groove which are provided by the inwardly-bowed middle 7 thereof permit a slight lateral rocking of the jaw 3 to compensate for slight irregularities in the article

10 gripped by the jaws.

It will be noted that the two said wrench members can be readily assembled and taken apart by the use of bolt 12. Furthermore, the use of a destructible pivot pin for the joint is obviated. Instead, when a bolt 12 becomes worn from use and the joint becomes loose and insecure, it is a simple matter to replace the worn bolt.

Having thus described my invention what I claim as new and desire to secure by Letters

20 Patent is:

A pipe wrench, comprising a fixed jaw formed with a transverse groove, said groove being formed in an axial direction with an inwardly-bowed center portion, a pivotal jaw provided 25 with a transverse cylindrical projection constructed to rotatably engage in said groove and to be rockably supported on said inwardly-bowed center portion thereof, said cylindrical projection being formed with an arcuate slot concentrically 30 thereof, a removable bolt passing transversely through the fixed jaw from the back thereof and intersecting said groove in the region of said center portion, and said bolt being provided with a shank adapted to be slidably seated in said arcuate slot of said cylindrical projection.
